ATTORNEY

UNITED STATES PATENT OFFICE.

HENRY F. W. BENZE, OF AMELIA, NEBRASKA.

SMOKER'S SHIELD.

1,196,646.

Specification of Letters Patent. Patented Aug. 29, 1916.

Application filed March 23, 1916. Serial No. 36,231.

To all whom it may concern:

Be it known that I, HENRY F. W. BENZE, a subject of the Emperor of Germany, and having filed a declaration of intention to 5 become a citizen of the United States, residing at Amelia, in the county of Holt and State of Nebraska, have invented certain new and useful Improvements in Smokers' Shields, of which the following is a specification.

This invention relates to a smoker's shield and more particularly to a shield which is attached to a match box whereby the smoker may ignite a cigarette, cigar or pipe from 15 the flame of a match without danger of the flame being extinguished from a gust of wind.

The invention further aims to provide a smoker's shield which will consist of a 20 canopy mounted upon a match box, the canopy being collapsible in a manner that will take but very little more space than the ordinary match box and one which, when it is desired to be used, can be quickly and 25 simply opened by releasing and holding the catch whereby the canopy will be automatically opened.

As a further object of the invention the device consists of a container in which the 30 match box is adapted to be held, being open at both ends for gaining access to the matches in the match box, the container having the collapsible canopy attached thereto and adapted to be held in open position by means of spring elements attached 35 at one end to the container and at the other end to the top of the canopy.

A further object of this invention is the provision of a smoker's shield which consists of comparatively few parts and is 40 simple in construction, but durable and well adapted to withstand the usage to which devices of this character are ordinarily subjected.

For a full description of the invention and the advantages and merits thereof, reference is to be had to the following description and the accompanying drawings, wherein is illustrated the preferred form of 45 my invention, in which;

Figure 1 is an end elevation showing the

canopy in open position. Fig. 2 is a front elevation. Fig. 3 is a vertical transverse section on the line 3—3 of Fig. 2. Fig. 4 is an end elevation showing the canopy in 55 closed position.

The ordinary safety match box is indicated by the numeral 1 and is mounted within a container 2 which is open at each end whereby the safety match box may be 60 mounted within the container and the side 3 of the container is provided with an elongated slot 4 through which access may be had to the scratch paper which is carried on each side of the match box in the ordinary manner. The top 5 of the container is provided on each end with flanges 6 in which are secured the ends of springs 7 and the opposite ends of the springs 7 are connected to flanges 8 which are carried by a 70 plate 9 which is inounted in spaced relation to the top 5 of the container and adapted to move vertically toward and away from the top 5 when the canopy is opened or closed. The canopy 10 is constructed of fabric and is of rectangular formation having its edges secured to the top of the container 5 and the under side of the plate 9 as indicated by Fig. 3 of the drawing. The front of the canopy is provided with an 80 opening 11 whereby the smoker may extend a cigarette, cigar or pipe within the canopy for lighting the same without danger of the flame of the match being extinguished. The lower edge of the side 3 of the box is provided with hinges 12 which receive the edge of a catch plate 13 hingedly mounted on the hinges 12 and having its free edge provided with a catch 14 designed to fit over the curved edge 15 of the plate 9. The opposite side of the container, at the upper edge thereof, is provided with a pair of clips 16 which have their ends curved to fit over the curved edge 17 carried by the edge of the plate 9 opposite to the edge upon 90 which the curved edge 15 is formed.

When the canopy is pushed downwardly into closed position against the tension of the springs 7, the edges of the flanges 6 and 8 will contact as indicated by Fig. 4 100 of the drawing. The catch plate 13 will then be swung into operative position caus-

ing the catch 14 to snap over the curved edge 15 and the members 16 will be snapped over the curved edge 17 and the plate 9 will be thereby held in locked position and the 5 canopy will be folded between the upper plate 5 of the container and the lower face of the plate 9. A longitudinal slot 18 is provided in the catch plate 13 and access may be gained through the slot 18 and the 10 slot 4 for scratching matches on the sides of the match box when it is desired to ignite a match under circumstances whereby the canopy will not necessarily be employed.

Attached to the plate 9 on the under face 15 thereof, is a supporting rod 19 which has a sponge 20 mounted on one end thereof and is adapted to be held against the bottom of the plate 9 by means of spring elements 21. This sponge 20 is kept dampened whereby 20 the match may be extinguished when the smoker has ignited the tobacco and desired to smother the flame of the match.

From the foregoing it will be observed that a very simple and durable smoker's 25 shield has been provided, the details of which embody the preferred form. I desire it to be understood however, that slight changes or modifications in the minor details of construction may be made without departing from the spirit of the invention or 30 the scope of the claims hereunto appended.

I claim:

1. The combination with a match box, of a container for the match box, a metallic 35 plate arranged in spaced relation to said container, fabric secured to the edges of the plate and to the top of said container, and resilient means for normally holding said plate in raised position.

40. 2. The combination with a match box, of a container for the match box, of a fabric canopy of the same perimetric shape as the container arranged above the top of the container and secured thereto, and means for 45 resiliently supporting the said canopy.

3. The combination with a match box, of a container for the match box, a collapsible canopy including a plate disposed in spaced relation to the container, and provided with 50 curved edges, a catch plate hingedly carried by the container, and clips carried by the opposite side of the container, said clips and said catch plate adapted to be connected to the curved edges of said plate for holding 55 the said canopy in collapsed position.

60. 4. The combination with a match box, of a container for the match box, a collapsible canopy including a plate of the same size as the top of the container, fabric connected to the edges of the plate and to the top of the container and being open on one side, spring elements connected at their ends to the container and to the plate, and fastening elements carried by the container and adapted

to be secured to the edges of said plate when 65 said canopy is in collapsed position.

5. The combination with a match box, of a container for the match box having both of its ends open, a catch plate mounted upon one side of said container, collapsible means 70 mounted on said container, clips mounted upon one side of said container and adapted to engage with said collapsible means.

6. The combination with a match box, of a container for the match box, a collapsible 75 canopy including a plate of the same size as the top of the container, fabric connected to the edges of the plate and to the top of the container and being open on one side, spring elements connected at their ends to the container and to the plate, and fastening elements carried by the container and adapted to be secured to the edges of said plate when 80 said canopy is in collapsed position, and means secured to the bottom of said plate 85 and disposed within said canopy for snuffing the flame of a match.

7. The combination with a match box, of a container for the match box, the end edges of said container carrying upturned flanges, 90 a rectangular plate disposed above and in spaced relation to the said container and having its end edges bent downwardly to provide flanges, the longitudinal edges of the said plate being curved upwardly, spring 95 elements disposed in each end of the container and having their ends secured to the flanges on said container and to the flanges on said plate, and clips carried by the container and adapted to connect with the curved edges of the plate for holding said plate in close proximity to the container against the tension of said spring elements.

8. The combination with a match box, of a container for the match box, a collapsible 105 canopy carried by said container and provided with a metallic plate at its top, flanges carried by said container and by said metallic plate, resilient means interposed on the flanges on said container and the flanges 110 on said plate, means for holding said plate in lowered position against the tension of said resilient means, and means carried by said container for snuffing the flame of a match.

115. 9. The combination with a match box, of a collapsible canopy carried by the match box, resilient means for normally holding said canopy in open position, a catch plate carried by said box and provided with a 120 longitudinal opening, said catch plate adapted to hold one edge of the top of said canopy in closed position, and clips carried by the opposite side of said box and adapted to hold the opposite side of said canopy in 125 closed position.

10. The combination with a match box, of a container, a collapsible canopy carried by

said container at the upper portion thereof, and provided with a metallic top adapted to move vertically with respect to the top of said container for opening and closing said canopy, resilient means carried by said container and connected to the metallic top of said canopy for holding the top of said canopy in open position, and means for

holding the top of said canopy in contact with the top of said container. 10

In testimony whereof I affix my signature in presence of two witnesses.

HENRY F. W. BENZE.
